UNITED STATES PATENT OFFICE

FRANK KOTRBA, OF CHICAGO, ILLINOIS, ASSIGNOR TO JOHN F. MEYER, OF CHICAGO, ILLINOIS

DESIGN FOR AN AMUSEMENT TARGET CABINET

Application filed April 13, 1929. Serial No. 30,880. Term of patent 7 years.

To all whom it may concern:

Be it known that I, FRANK KOTRBA, a citizen of the United States, residing at Chicago, in the county of Cook and State of Illinois, have invented a new, original, and ornamental Design for an Amusement Target Cabinet, of which the following is a specification, reference being had to the accompanying drawing, forming a part thereof.

Fig. 1 is a perspective view and Fig. 2 is an end view on a smaller scale of an amusement target cabinet showing my new design.

I claim:

The ornamental design for an amusement target cabinet as shown.

FRANK KOTRBA.
